UNITED STATES PATENT OFFICE.

LEWIS J. DICKEY, OF BOSTON, MASSACHUSETTS, ASSIGNOR TO STANDARD COIN WRAPPERS, INC., OF BOSTON, MASSACHUSETTS, A CORPORATION OF MASSACHUSETTS.

COIN PACKAGE.

Application filed August 31, 1922. Serial No. 585,475.

To all whom it may concern:

Be it known that I, LEWIS J. DICKEY, a citizen of the United States, residing in Boston, in the county of Suffolk and State 5 of Massachusetts, have invented an Improvement in Coin Packages, of which the following description, in connection with the accompanying drawings, is a specification, like characters on the drawings representing 10 like parts.

This invention relates to a tubular package in which coins are assembled and packed and has for its object to provide a superior package for the purpose specified, which 15 can be produced at a minimum cost. To this end, the tubular package is made from a paper or like blank provided with parallel sides and having one end inclined and extended from side to side in a substantially 20 straight line, and having its other end provided with substantially straight sections which converge from the opposite sides and form between said sides a substantially 25 pointed end, which extends beyond said sides and has a tendency to spring outwardly after the blank is rolled into the form of a tube, and which enables the paper blank to be rolled into tubular form with the ends of 30 the tubular convolutions at each end of the tubular package and which are formed by a side of the paper blank, to lie in the same radial plane, and have the different convolutions at the entrance end of the tubular package in contact with each other throughout 35 their circumferential length and thus provide the tubular package with an entrance end for the coins, which is practically circular and affords a free and unobstructed 40 passage for the coins into the package, and enables the coins to be packed in a minimum time.

The opposite end of the tubular package is provided with an internal annular bead, which forms a support for the stack of coins and which is formed by rolling or folding 45 inwardly the lower end of the tubular package.

The particular features of the invention will be pointed out in the claims at the end 50 of this specification.

Fig. 1 is an elevation of a tubular coin package embodying this invention.

Fig. 2, a longitudinal diametrical section 55 of the package shown in Fig. 1.

Fig. 3, a plan view of the package shown in Fig. 1.

Fig. 4, a developed view of the paper blank from which the package shown in Fig. 1 is formed, and

Fig. 5, a plan of a strip from which the blanks shown in Fig. 4 are economically produced.

Referring to the drawing *a* represents a tubular coin package embodying this invention and provided at its lower end with an internal annular bead *b* forming a bottom support for the stack of coins, not shown, but which are inserted into the tubular package *a* through its upper or entrance end, 70 which is free and unobstructed for the entrance of the coins, as will be described.

The tubular package *a* is made from a flat paper blank 8, see Fig. 4, which is provided with parallel sides 10-12, a substantially 75 straight diagonal or inclined end 13, and a pointed end which is of suitable shape to provide the blank with a projecting portion intermediate the sides 10-12 and extended beyond said sides, and which is formed by 80 substantially straight sections 15-16 of unequal length, extended from the sides 10-12 respectively, and converging toward each other. The end edge 15 is parallel with the end 13, so that the blanks may be cut from 85 a continuous strip of paper, without material waste, as hereinafter set forth.

The converging sections 15-16 are, as said, of unequal length and are brought to a point relatively near the side edges, 12, 90 for a purpose, as will be described. By providing the upper end of the flat blank with the sections 15-16, which extend from the parallel sides 10-12 and converge, said blank is provided with an end, which, when 95 the blank is rolled into the form of a tube, forms a substantially pointed end portion 14 between the sides and projecting beyond the upper ends of said sides, which pointed end portion 14 projects beyond a straight 100 line joining the upper ends of the parallel sides 10-12 and indicated by the dotted line 20. The pointed end portion 14 of the blank has a very important function when

the flat blank is rolled into the form of a tube with the pointed end portion 14 within and constituting the innermost convolution of the tube as represented in Fig. 2. The substantially pointed end portion 14 has a tendency to spring outwardly or uncoil, 110 which enables the flat blank to be wound into a tube having parallel ends, with the portions of the parallel sides 10-12 forming

circumferential edges of convolutions of the tubular package and with the circumferential edges formed by the side 10 in the same radial plane and those formed by the side 5 12 in another radial plane, which is parallel with the first mentioned radial plane. By locating the point relatively near the edge 12, which is accomplished by having the edge or section 15 considerably greater in 10 length than the edge or section 13, it is possible to form a greater number of wrappers (for coins of a given diameter) from a strip of paper than if the point where located substantially midway between the edges 15 10—12.

The flat blank 8 is wound upon a suitable mandrel, not shown, beginning at the pointed end portion 14, and the lower end of the tube thus formed is folded or crimped inwardly to form the internal bead 5. The tubular package *a* thus formed is then removed from the mandrel, which permits the pointed end portion 14 to uncoil or spring outwardly until arrested by the next 25 convolution, at which time the upper end of the side 12, will bear against the next convolution in substantially the same plane through a radius of the tubular package as the upper end edge of said next convolution. 30 As a result, the edges of the upper ends of the convolutions of the tubular package at the entrance of the latter, contact with each other, and the innermost convolution is not separated from the next adjacent convolution by a space, as would be the case if the side 12 of the blank constituted the highest point of the pointed end of said blank, that is, if the end portion 14 were omitted from the blank and the upper end of the latter 40 terminated at the dotted line 20. The result obtained with a blank having a pointed end portion intermediate its parallel sides 10—12 and projecting beyond the upper end of its highest side, is illustrated in Fig. 3, 45 wherein it will be seen that the innermost convolution of the tubular package bears against the next adjacent convolution and is not separated therefrom, and that the projecting end portion 14 also bears against 50 the next adjacent convolution. As a result the entrance mouth of the package is practically circular and, being slightly larger in diameter than the body portion of the tube, offers no obstruction to the coins entered 55 therein. In other words, the upper end por-

tion of the side 12 of the blank has a continuous bearing with the next adjacent convolution for the circumferential length of the innermost convolution, and does not bear at its end and again at a point a substantial 60 distance from said end, so that the portion of the innermost convolution forms the cord of an arc with a portion of the next adjacent convolution, which construction is objectionable as the entrance mouth of the package 65 in such case would not be practically circular and free and unobstructed, but would be decidedly non-circular and obstructed for the free and easy entrance of the coins.

Furthermore the blank 8 enables the coin 70 packages *a* to be produced at a minimum cost, inasmuch as said blanks may be cut with the least possible waste from a strip of paper having parallel sides and such as is now commonly made.

In Fig. 5, 22 represents a strip of paper from which the blanks 8 are produced. The strip of paper 22 which is provided with parallel sides is then cut transversely from side to side, as indicated by the dotted lines 23, and is also cut transversely by shorter cuts which extend from one side of the strip and intersect the cuts 23 extending from side to side. The shorter cuts are represented by the dotted lines 24. 80 85

It will be seen by reference to Fig. 5, that the only waste stock occasioned by the formation of the pointed portion 14 of the blank 8, is the small triangular section 25 of the paper strip 22, which is practically negligible. 90

Claims:

1. A coin wrapper composed of a blank wound into a plurality of convolutions with their upper side edges in the same transverse plane, the innermost convolution terminating in a point, formed by angular sections of unequal length, and located between the middle and the upper side edge of said innermost convolution, the lower side edges of said convolutions being inwardly crimped. 95 100

2. A coin wrapper consisting of a blank having substantially parallel side edges, a straight diagonal or inclined end, and a pointed end formed by a long section parallel to said diagonal straight end, and a short section angular to said long section, said point being located relatively near one of said parallel sides. 105
